United States Patent Office.

JAMES MAXEY, OF KEWANNA, INDIANA.

Letters Patent No. 72,310, dated December 17, 1867.

IMPROVEMENT IN CHURNS.

The Schedule referred to in these Letters Patent and making part of the same.

TO ALL WHOM IT MAY CONCERN:

Be it known that I, JAMES MAXEY, of Kewanna, in the county of Fulton, and in the State of Indiana, have invented certain new and useful Improvements in Churns; and do hereby declare that the following is a full, clear, and exact description thereof, reference being had to the accompanying drawings, and to the letters of reference marked thereon.

In the annexed drawings, making part of this specification, A represents the body of the churn, which may be made of any suitable size, and in any of the known and usual ways in which upright or vertical churns are made. B represents the dasher-staff, which has a bearing in the bottom of the churn-body at its lower end, its upper end passing through a suitable hole or opening in the top E, and being provided with a pinion, F. H H represent two standards, which are erected upon the cover E, and in which a horizontal shaft, I, has its bearings. Upon one end of this shaft is a gear-wheel, G, and upon the other, a crank-handle. The wheel G gears into the pinion F, and serves to give motion to the dasher-staff. Upon the lower end of the dasher-staff are two series of arms, a a, and secured across the ends of the corresponding arms, are the paddles C C. D represents a gauze-wire wheel which surrounds the dasher-staff, a short distance above the upper arms a a, said wheel being a little less in diameter than the inner diameter of the churn-body. This wheel answers not only to break the cream or milk as it is poured into the churn, but also prevents the cream from splashing, and assists in breaking it when it does splash. This churn is simple and cheap and effective, and one which is easily operated.

Having thus fully described my invention, what I claim as new, and desire to secure by Letters Patent, is—

The arrangement of the churn-body A, standards H H, shaft I, wheels G and F, and staff B, provided with the wheel D and the paddles C C, as and for the purpose set forth.

In testimony that I claim the foregoing, I have hereunto set my hand, this 1st day of October, 1867.

JAMES MAXEY.
